UNITED STATES PATENT OFFICE.

GEORGE WILLIAM BERRY, OF ROSE BAY, NEAR SYDNEY, NEW SOUTH WALES, AUSTRALIA, ASSIGNOR TO THE WIRELESS HINGE MANUFACTURING COMPANY LIMITED, OF SYDNEY, AUSTRALIA.

CONSTRUCTING LID-HINGES FOR SHEET-METAL RECEPTACLES.

1,223,848.

Specification of Letters Patent. Patented Apr. 24, 1917.

Application filed April 22, 1916. Serial No. 93,013.

To all whom it may concern:

Be it known that I, GEORGE WILLIAM BERRY, a subject of the King of Great Britain, residing in Rose Bay, near Sydney, in the State of New South Wales, Commonwealth of Australia, engineer, have invented new and useful Improvements in Constructing Lid-Hinges for Sheet-Metal Receptacles, of which the following is a specification.

This invention relates to the manufacture of pressed sheet metal receptacles comprising a body portion formed with bulbed tongues and a rimmed lid portion adapted to fit over the body portion with hinge pintles formed integrally upon the lid rim upon which pintles said bulbed tongues are closed to form a wireless hinge joint uniting said body and lid. The invention is applicable to rectangular receptacles, or receptacles other than rectangular having one flat side.

The object of the invention is to provide commercially effective means whereby integral pintles may be produced with certainty by bending and cutting the lid rim stock in a certain succession of die press operations, and to obviate the losses and avoid the failures hitherto encountered as a consequence of the bending die jumping and gripping the stock and mutilating it. It is necessary that the hinge pintles be uniform in dimensions and identical in form and shaped to fit rotatably free in the bulbs on the tongues which form pintle bearings.

Minimum cost of manufacture is a primary consideration in the production of sheet metal receptacles such as hinged lid tobacco boxes and the like, and it is necessary that the hinge members of such receptacles shall be formed and engaged in a succession of automatic die press operations in order to minimize labor cost and insure rapid production and uniformity of product. The effectiveness of each of the several die press operations depends necessarily upon the effectiveness of the preceding step. A failure in one step in the succession of operations will necessarily involve difficulties in the succeeding steps, which may interfere with the feed of the press in which the operations are conducted, or may result in mutilation of the hinge members and

cause the production of imperfect receptacles which cannot be marketed.

The known method of forming integral hinge members from the body stock has been proven sufficiently effective. However, the known method of forming integral pintle members on the lid stock has not been commercially successful due to the deformation of the thin stock of the lid in an early operation of forming the lid, and the consequent impossibility of centering the slender overhanging parts which were partially detached from the main part of the lid stock in such step with the result that the forming dies to bend these parts to form pintles would grip and jump said slender overhanging parts and so deform them that they were in a large proportion of cases made useless as hinge members. Due to the said deformation of the pintles difficulties arose in the final step of closing the bulbed tongues in the body stock around the pintles so as to leave said lid pintles free to turn in the bulbs of the tongues.

According to the said known method of manufacturing integral wireless hinge pintles on sheet metal receptacles in a compound die press, spare stock left on one rim of the lid in the lid-forming operation was slotted back so as to leave two slender laterally projecting tongues on said stock. In a succeeding operation it was attempted to die roll or bend the depending stock and the tongues projecting laterally therefrom so as to form therefrom a tubulous or fluted pintle of which the laterally projecting portions were, in a later stage in the operation, introduced under the bulbed tongues on the body stock, and said bulbed tongues then closed down to embrace them and so to complete the formation and fitting of the hinge.

In carrying out the present invention a depending piece of stock is left on one of the lid rims in the lid forming operation, to provide material for the hinge pintles.

In the first die operation to form hinge pintles on the lid, the depending margin of the rim stock is die rolled to a tubulous or fluted section, and in a succeeding operation two or more slots, depending upon the number of hinge pintles required, are made in the rim stock above the die rolled marginal portion thereof so as to form from the ad-

ja⁵gent portions of the die rolled margin two or more pintle members as the case may be, each adapted to be inclosed within bulbs formed on tongues in the body stock.

15 The ends of the depending portion of the rim lid stock are rounded in the lid forming operation, so that when the marginal portion is die bent burring or ragging will be obviated and the unattached ends of such 70 marginal portion will be rounded, thereby insuring a free fit for the pintles in the bulbs of the tongues.

16 The accompanying explanatory drawings illustrate formed body and lid and the hinge members in successive stages of their production and fitting in a compound die press, and they illustrate also the construction of the punches and die blocks with their essential accessory parts in which the forming, bending, slitting and closing operations are severally effected in such press.

17 Figures 1 to 7 are perspective views which show the progress of the manufacture of the hinge in four stages. Figs. 1 and 2 show the 25 body and lid as delivered for the making and fitting of integral hinges thereon, Figs. 3 and 4 the same parts after the first die press operation, Figs. 5 and 6 the same parts after the second die press operation, 30 and Fig. 7 the two parts as fitted together in the third die press operation. In each die press operation double punches and dies are used and the body and lid members are each operated on simultaneously at each 35 successive movement of the punches.

18 Three sets of dies and punches are installed in a multi die press which is fitted with means for transferring the work in progress from the feed to the first die block, 40 thence at the completion of the first movement of the press to the second die block, thence on the completion of the second movement of the press to the third die block, and thence ejecting the completed hinged 45 receptacle out of the machine. The means for conveying the parts into and out of the machine and for transferring them from die block to die block successively there-in does not form part of the present invention.

50 Figs. 8 and 9 are transverse sections through the first punch and die block used in carrying out the present invention; as shown bulbed tongues and clearnace space 55 are formed in the receptacle body and the depending part of the lid stock die rolled to form a tubulous or fluted edge or "false wire". Fig. 8 shows the first operation punch before its descent, and Fig. 9 shows 60 said punch in the closed position on the die block with the formed metal contained between the punch and the die block.

65 Figs. 10 and 11 are corresponding views showing the punch and die block in the next step of the manufacture. In this step

the bulbed tongues are slotted and bent outwardly and the lid stock is slotted back rearward of the ends of the tubulous "false wire" to form same into pintles engageable by the bulbed tongues. Figs. 12 and 13 are 70 similar views illustrative of the last stage of the manufacture, in which the bulbed tongues are closed over the projecting pintle ends.

75 Fig. 14 is a perspective view of the punch and die block for performing the operations indicated in Figs. 3, 4, 8 and 9. Fig. 15 is a similar view of the punch and die block used for performing the operations already explained with reference to Figs. 5, 6, 10 80 and 11. Fig. 16 is a similar view of the die members for performing the operation shown in Figs. 12 and 13. Fig. 17 is a rear side view of one member of the top die shown in Fig. 16. In Figs. 14, 15 and 85 16 the top die is tilted over to expose its under face to facilitate description thereof. Fig. 18 is a perspective view of the forming punch and die block used for producing a lid (Fig. 2) from flat stock; 90 Fig. 19 is a vertical section explanatory of the die press operation in which the lid blank (Fig. 2) is produced by means of the punch and die Fig. 18.

95 The numeral 10 designates a punch and die block for cutting and forming the lids from flat stock indicated by dotted line 10'. The die block (see Figs. 18 and 19) is formed of a stout block of metal having a deep groove 11 formed vertically therein 100 and corresponding with the lid shape; on one side of said groove two inwardly projecting notch cutters 12 are fitted. The inner side of each of said cutters 12 is slightly recessed (13) and the width of the 105 mortise groove is greater between these cutters than at its other parts. A drawing ring 14 is fitted slidably in the groove 11, and is a neat sliding fit over a forming block 15; the shape of this block 15 is counterpart to the shape of the lid blank to be 110 made.

The ring punch 16 is so shaped on its outer periphery that it will run neatly into and completely fill the groove 11 in the die 115 block.

The outer ring of the die block is splayed up for shearing at the edge of the groove 11. When forming lids a sheet of stock is placed over the die block and the punch 120 dropped thereon. The edges of the cut stock are forced downwardly around the forming block 15 by the continued downward movement of the punch ring 19 and follower 18, and the edges of the cut stock 125 are pressed neatly downward around the top of said block, the rims on the lid being thus formed.

The inserted notch cutters 12 and counterpart undercut grooves 19 in the punch 130

ring 16 are tapered to insure draw of the notched part of the rim around the forming block.

The follower 18 recedes into the punch 5 ring as same enters the die block; when the punch is raised it carries with it the formed lid, and same is ejected from the punch by the follower 18 when it is pushed downwardly when the punch ring is nearing the 10 limit of its upward travel. 20 is a rectangular sheet metal receptacle body which is shown by way of example but need not necessarily be of this or any approximately similar shape so long as it has one flat side. 15 21 is a lid for said body, produced as already described. The back rim of this lid is made deeper between the notches 23 than its depth elsewhere; the centrally disposed depending portion 22 provides stock for the formation 20 of hinge pintles.

The notches 23 extend more or less (see Fig. 2) into the rim stock above the depending part 22 and curve the ends of said depending part as shown.

25 In order to form a hinge, the receptacle body 20 is placed over one side of a die block 24 (see Fig. 8) which is fitted on a bed 25, and the lid blank is set over the die block 26 on the opposite side of the said bed. The die block 24 is formed with two protuberances 27 having their upper surfaces and outer ends rounded off and their inner ends cut vertically. A counter-sink 28 extends from one protuberance 27 to the 30 other. The punch 29 is fitted to a ram 30 and is formed with countersinks 31 which are counterparts of the protuberances 27. A depressing piece 32 on the punch 29 sets into the countersink 28 in the die block 24 when 35 the punch is down.

When the punch 29 descends on to the die block the protuberances 27 form outwardly disposed bulbs 33 on the wall of the receptacle body and the depressing piece 32 40 forms an inwardly disposed depression 28' between the bulbs.

The inner edges of the countersinks 31 co-acting with the square inner edges of the parts 27 shear vertical incisions 34 in the 45 stock at the inner ends of said bulbs 33 in the forming operation. The slitting and forming of the bulbs 33 is performed simultaneously, and the bulbs are thus finished with their adjacent ends open to accommodate 50 the hinge pintles on the lid (see Fig. 3).

The lid die block 26 is formed with a longitudinally disposed rib 36 of the same length as or slightly longer than the depending portion 22 of the lid rim. The top 55 punch 37 is formed with two parallelly disposed drawing ribs 38 and 39, with intervening groove which is counter-part to the rib 36. The rib 38 is slightly deeper than the rib 39 and as the punch descends the said rib 60 38 bends the edge part of the depending

portion 22 of the lid rim over the inner edge of the rib 36 before the rib 39 bears on the upper part of the depending portion of the lid. The bending and pinching of the edge of the stock margin insures accurate drawing and bending to form the tubulous or fluted edge as shown in Fig. 4 of the drawings. The ribs 38 and 39 set into shallow countersinks 40 and 41 in the die block. Hinge pintles are formed in a later operation by slotting out stock rearward of the tubular or fluted edge. The body and lid are now removed to the second die blocks 43 and 44, respectively. The die block 43 is mounted on a bed 45. It carries two forming cutters 46 of angular shape in cross section and rectangular in plan. Their inner faces are vertical and their outer faces chamfer forwardly from the upper face. These spreading cutters 46 are located on 85 the die block 43 so they set beneath the bulbs 33 on the receptacle body. The punch 47 is carried on a ram 48 and rectangular recesses 49 are formed in said punch face 47 to aline with the cutters 46 and slit the 90 stock in the back of the receptacle body along the upper sides and downward slightly beyond the outer ends of the bulbs. The rectangular pieces of metal bounded by the slits so made are pressed outwardly from 95 the back of the receptacle body in the closing of the punch 47, forming bulbed tongues see Figs. 5 and 11 of the drawing. A pocket 51 is formed in the face of the die block 43, (see Fig. 15) to accommodate the 100 depressed portion 28' on the back of the receptacle body.

The die block 44 on the opposite side of the bed 45 is mortised as shown at 52 counterpart to punches 53. The said punches 105 53 slot out portions 54 of the lid stock as shown by the dotted lines in Fig. 4 of the drawings, thereby to carry back the notches 23 as shown at 65 Fig. 6 thus forming the ends of the bent margin 42 into hinge pintles 55 which are adapted to be engaged by and pivot in the bulbs 33 on the back of the receptacle body.

The ram 48 is fitted with a spring controlled stripper saddle 56 shaped to accommodate the punches 53. A recess 58 formed in the stripper 56 accommodates the central portion of the bent margin 42 on the back of the lid.

When the stock 54 has been removed and 120 the bulbed tongues have been raised as shown in Figs. 5 and 11, the ram 48 is raised and the receptacle body and lid are removed from the die block.

The body is then placed over the vertical 125 side of the closing die block 59 and the lid is placed on the opposite side of the said die block inclining toward the back of the body, so that the pintles 55 come directly beneath the bulbs 33 which are then closed over the 130

pintles 55 by the downward movement of the compound closing punch 60 (see Figs. 12 and 13).

The punch 60 of the closing die is formed in two parts, one part 61 being fixed in the ram and the other part 62 being slideable against backing springs 63. The slide 62 normally projects below the fixed part 61, and as the punch descends the two parts 61 and 62 are brought to bear one on either side of the bulbous part of the raised tongues and set the said tongues back into their original positions now inclosing pintles 55.

The contiguous lower corners of the two parts of the closing punch 60 are corner fluted as at 64' to permit of the punch coming hard home without injuring the bulbs 33, the "false wire" 42 or the pintles 55.

The fixed part 61 of the closing punch is formed with depending projections 64 which are adapted to pass through the slots 65 on the lid stock. The faces of the depending projections 64 approximate in size to the outer ends of the bulbed tongues, and bear upon the upper sides and rounded ends of the said bulbs.

The closing die block 59 is formed with a central depression 66 to accommodate the depressed portion 28' on the back of the receptacle body, and in the face of the said die block at the ends of the depression 66 are recesses 67 shaped to receive the edges of the stock from which the pintles are formed.

35 The bulbs 33, when the tongues are closed, are sufficiently large to permit free pivotal movement of the pintles 55 when the lid is being opened and closed. The object in rounding off the points of the depending stock 22 from which the "false wire" 42 is formed is to remove and prevent subsequent formation of bur or rag and so insure for said pintles free movement in the said bulbs.

In the old process of forming the lid pintles referred to a large percentage of the pintles were deformed with the result that it was impossible to neatly inclose said pintles by the bulbed tongues, and when the tongues were closed upon such deformed pintles it was impossible to open the lids without straining or distorting the hinges. When a hinge is mutilated in manufacture and is strained or buckled in opening the lid it is impossible to again close the lid 55 with the facility required in practice.

What I do claim is:

1. A process for hingedly connecting a sheet metal receptacle body and rimmed lid, which consists in producing bulbed tongues on said body portion, bending a depending marginal portion of the lid rim stock to a tubulous or fluted section, slotting out rim stock rearward of the tubularly bent margin thereof thereby leaving portions of said tubulous or fluted margin to form pintles, po-

sitioning said pintles under said tongues, and inclosing said tongues thereover.

2. The herein described improvement in the manufacture of sheet metal receptacles with rimmed lids hingedly attached thereto by pintles which are formed of the lid rim stock and are embraced by bulbed tongues on the body member, which consists of the following named operations in successive order:—firstly bending a depending margin of said rim stock to form a tubulous or fluted edge thereon, and secondly slotting back said stock rearward of said tubulous edge, thereby forming pintles engageable by said body tongues.

3. An improved process of hingedly connecting a rim lid to a receptacle body constructed in sheet metal, which consists in forming the lid with a centrally disposed depending portion on one of the rims thereof, bending the marginal portion of said depending stock to a tubulous or fluted edge and thereafter forming pintles from the ends of said tubulous or fluted lid edges by cutting away portion of the lid stock above and around the ends of the same; forming two open end bulbs on the back of the receptacle body, slitting the body stock over the top and outer ends of each of said bulbs and then bending the stock bounded by said incisions outwardly to form bulbed tongues, introducing said pintles beneath said bulbs, and inclosing said tongues over said pintles.

4. An improved process of hingedly connecting a receptacle body and a rimmed lid therefor constructed of sheet metal, consisting in forming the lid with a depending portion on the back rim thereof, then forming a bent edge on the margin of said depending portion, subsequently producing pintles at the ends of said bent edge by slotting out portions of the rim above the ends of the same, forming bulbed tongues on the back of the receptacle body, and finally inclosing said tongues over said pintles.

5. A process for hingedly connecting a sheet metal receptacle body and rimmed lid, which consists in producing bulbed tongues on said body portion, forming one rim of the lid with a depending portion terminated by curved notches extending into the rim stock above said depending portion thereof, bending the depending portion of the rim stock to a tubulous or fluted section, slotting out rim stock rearward of the tubularly bent margin thereof inward from the beforementioned notches at the ends thereof, thereby leaving the end portions of said tubulous or fluted margin projecting to form pintles, introducing said pintles into said bulbed tongues, and inclosing said bulbed tongues thereon.

6. The herein described improvement in the manufacture of sheet metal receptacles with rimmed lids hingedly attached thereto

5 by pintles which are formed in the lid rim stock and are embraced by bulbous tongues on the body member, which consists of the following named operations in successive order:—firstly, forming one rim of the lid with a depending portion terminated by curved notches extending into the rim stock above said depending portion thereof, bending the depending portion of the rim stock 10 to a tubulous or fluted section, slotting out rim stock rearward of the tubularly bent margin thereof inward from the beforementioned notches at the ends thereof, thereby leaving portions of said tubulous or fluted 15 margin to form pintles, and introducing said pintles into said bulbous tongues and inclosing said bulbous tongues thereover.

7. The herein described improvement in the manufacture of sheet metal boxes with 20 rimmed lids hingedly attached thereto by pintles formed integral with the lid rim,

which process consists in the following named operations in successive order:—firstly cutting two curved notches at the ends of a depending margin in the stock on one side of the lid rim; secondly, bending the depending margin of the rim stock between such notches, thereby forming a tubulous or fluted edge thereon; and thirdly slotting back said rim stock adjacent both said notches and rearward of said tubulous edge, thereby forming the end portions of said tubulous or fluted edge into projecting pintles adapted to be engaged in bulbous tongues on the body portion of the receptacle. 25 30 35

In testimony whereof I have signed my name to this specification in the presence of two subscribing witnesses.

GEORGE WILLIAM BERRY.
